STAMP DISPENSER

George J. Perkins, 44 Hawthorne Road,
Barrington, Ill.

Filed Mar. 18, 1964, Ser. No. 79,074

Term of patent 14 years

(Cl. D52—2)

FIG. 1 is a right side perspective view of a stamp dispenser showing my new design;

FIG. 2 is a side elevational view of a stamp dispenser showing the same side that is shown in FIG. 1 with the side opposite being identical with the side that is shown;

FIG. 3 is a rear elevational view of the stamp dispenser of FIG. 1;

FIG. 4 is a top plan view of the stamp dispenser of FIG. 1;

FIG. 5 is a bottom plan view of stamp dispenser of FIG. 1.

I claim:

The ornamental design for a stamp dispenser, substantially as shown.
